UNITED STATES PATENT OFFICE.

ELMER E. FISHER, OF KOKOMO, INDIANA.

FOLDING CHAIR.

1,349,271.

Specification of Letters Patent. Patented Aug. 10, 1920.

Application filed October 22, 1919. Serial No. 332,428.

To all whom it may concern:

Be it known that I, ELMER E. FISHER, a citizen of the United States, residing at Kokomo, in the county of Howard and State of Indiana, have invented a new and useful Folding Chair, of which the following is a specification.

This invention relates to folding chairs, one of its objects being to provide a chair having a flexible seat and back rest, the several parts of the structure being so assembled that the back cannot become dislodged from proper position relative to the seat as long as the seat is occupied, but can be shifted forwardly and downwardly relative to the unoccupied seat thereby to fold the seat supports and house the chair back within the fold of the seat.

A further object is to so construct the device that, by pulling upwardly on the back or pressing downwardly on the front the folded seat will be opened out to active position with the seat back in proper place.

Another object is to provide a folding chair which is simple and durable in construction, compact when folded, and strongly braced when in use.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth.

In the accompanying drawings the preferred form of the invention has been shown.

In said drawings—

Figure 1 is a central vertical section through the chair set up for use.

Fig. 2 is a plan view thereof, a portion of the seat fabric being broken away.

Fig. 3 is a view similar to Fig. 1 and showing the chair partly folded.

Fig. 4 is a similar view showing the seat entirely folded.

Fig. 5 is a side elevation of a modified form of chair set up for use.

Fig. 6 is a side elevation showing the same folded.

Fig. 7 is an enlarged section on line 7—7, Fig. 5.

Referring to the figures by characters of reference, 1 designates parallel legs connected at their upper ends by a rounded seat strip 2 and extending between these legs are parallel legs 3 connected at their upper ends by a seat strip 4 preferably rounded as shown. The legs 1 and 3 are pivotally connected at intermediate points where they cross and as shown at 5 and the lower portions of the legs 1 and of the legs 3 can be connected by cross braces or rounds 6. A fabric seat bottom 7 or a bottom of any suitable flexible material is secured to the two strips 2 and 4 and has the added function of limiting the movement of the strips 2 and 4 away from each other.

Journalized in the legs 1 near the upper ends thereof is a roller 8. Flexible straps 75 of fabric, leather, or other suitable material, and which have been indicated at 9, are secured at one end to the strip 4 and extend over the roller 8. The front ends of the straps are secured to the front ends of the 80 sides of a frame 10 which is located between the legs 1 and the legs 3 and is pivotally connected, at its rear end, to the lower ends of the side strips 11 of the chair back. A rod 12 serves to connect and brace the 85 frame 10 and back strips 11. The back strips 11 extend outside of the legs 3 and have their lower ends rounded, as at 13 to bear on the legs 1. A cross strip or round 90 14 connects the strips 11 near their upper ends. A back rest 15 formed of suitable material is secured to the front faces of the back strips as shown. Pins 16 are extended from the legs 3 in front of the strips 11 and pins 17 are extended from said legs back of 95 strips 11.

When the chair is set up for use, as shown in Fig. 1 the strips 11 bear down on the legs 1 and are prevented from sliding downwardly on said legs by the straps 9 which pull on the frame 10. When it is desired to fold the chair the back structure is swung forwardly and pressed downwardly. The frame 10 will thus be caused to pull on the straps 9 and they, in turn will draw the strips 2 and 4 toward each other thereby swinging the legs 1 and 3 so as to fold the chair. As the back structure moves downwardly the rest 15 will move into the fold of the bottom 7, as shown in Fig. 4 and the 110

entire device will thus be completely folded into a compact bundle. Furthermore shoulders 18 on the strips 11 will engage shoulders 19 on the legs 1. Thus the folded chair 5 can be carried by means of the back thereof. To set up the chair for use the foregoing 10 operation is reversed. The back section is thrust downwardly so as to disengage the locking means and is then pulled upwardly and is limited in its movement by the pins. It is then swung back about its points of 15 contact with the legs 3 and said legs will be shifted relative to the legs 1 so as to draw the seat 7 taut. Or, if preferred, the front of the seat can be pushed down and will cause the seat to spread and the back to move upwardly.

It is to be understood that the ends of the strips 2 and 4 project laterally beyond the 20 seat 7 so as to limit the free movement of the side strips 11 of the back frame, the projecting ends of the strip 4 supporting the strips 11 when the chair is in use.

The seat 7 can be of any construction 25 desired, it only being necessary to provide a seat that will fold.

In Figs. 5, 6 and 7 another form of the chair has been illustrated. By referring to these figures it will be noted that the side 30 strips 20 of the chair back are provided, within their inner sides, with longitudinal grooves 21 and projecting into these grooves are guide pins 22 extending from the upper portions of the legs 23, arm rests 24 are pivotally connected to the upper sides of the strips 20 as shown at 25 and are connected by 35 hinges 26 to the upper ends of the supports 27. The lower ends of these supports are pivotally connected, as at 28, to the legs 29 40 of the chair. The lower ends of the strips 20 are attached to a frame 30 similar to the frame 10 heretofore described.

It will be obvious that when the back of this modified form of chair is thrust downwardly the arm rests 24 will fold against the 45 supports 27 and the strips 20 will slide downwardly along the legs 29 until the parts are brought to the position shown in Fig. 6.

What is claimed is:—

50 1. A folding chair including pivotally connected crossed pairs of legs, a flexible seat connected to the upper ends of the legs, a guide member carried by one pair of legs close to the front of the seat, a back structure 55 movably mounted on said pair of legs, a connection between the lower end of said structure and the back of the seat, said connection extending over the guide, and means for limiting the upward movement of said structure relative to the seat.

60 2. A folding chair including crossed pairs of legs pivotally connected, front and back seat strips connecting the upper ends of the legs of the respective pairs and extending laterally therebeyond, a flexible seat con-

necting said strips, connected back strips at opposite sides of the seat and movable between the projecting ends of the seat strips, a guide connecting the legs of one pair close to the front of the seat, a connection between 70 the back seat strip and the lower ends of the back strips and extending over the guide, said back strips normally bearing on the legs of one pair, and means for limiting the upward movement of the back strips relative 75 to the seat.

3. A folding chair including pivotally connected pairs of legs, a flexible seat connected thereto and foldable therebetween a back structure including a back rest, said structure being braced in active position by the legs and the back portion of the seat, and means operated by the downward movement of the back structure relative to the seat for folding the legs and for housing the 80 back rest within the fold of the seat.

4. A folding chair including pivotally connected pairs of legs, a flexible seat carried thereby and having laterally projecting front and back strips, a back frame movable freely 90 relative to the legs and seat and between the projecting portions of said back and front strips, the legs of one pair constituting supports for the lower end of the back frame, means operated by the downward movement 95 of the back frame relative to the seat for swinging the pairs of legs to folded position and for folding the seat between the legs, and for limiting the upward movement of the back frame relative to the seat.

5. A folding chair including pivotally connected pairs of legs, a flexible seat connected thereto and foldable therebetween a back structure including a back rest, said structure being braced in active position by 105 the legs and the back portion of the seat, and means operated by the downward movement of the back structure relative to the seat for folding the legs and for housing the back rest within the fold of the seat and coöperating means upon the back structure and one of the pairs of legs for fastening the chair in folded position.

6. A folding chair including pivotally connected pairs of legs, a flexible seat connected thereto and foldable therebetween a back structure including a back rest, said structure being braced in active position by the legs and the back portion of the seat, and means operated by the downward movement 115 of the back structure relative to the seat for folding the legs and for housing the back rest within the fold of the seat, coöperating means upon the back structure and one pair of legs, and means upon said back structure and coöperating with the seat, for holding the chair folded when supported by the back structure.

7. A folding chair including pivotally connected crossed pairs of legs, a flexible 130

seat connected to the upper ends of the legs, a guide member carried by one pair of legs close to the front of the seat, a back structure movably mounted on said pair of legs, 5 a connection between the lower end of said structure and the back of the seat, said connection extending over the guide, there being longitudinal grooves in the inner sides of the back structure, and guide pins extending from the legs of one pair and projecting 10 from the legs of one pair and projecting into the grooves.

8. A folding chair including pivotally connected crossed pairs of legs, a flexible seat connected to the upper ends of the legs, 15 a guide member carried by one pair of legs close to the front of the seat, a back structure movably mounted on said pair of legs, a connection between the lower end of said structure and the back of the seat, said con-

nection extending over the guide, there being longitudinal grooves in the inner sides of the back structure, and guide pins extending from the legs of one pair and projecting into the grooves, supports hingedly connected to the front legs, and arm rests 25 hingedly connected to the sides of the back structure and extending over and hinged to said supports, the arm rests and supports being foldable together during the folding of the chair.

In testimony that I claim the foregoing as my own, I have hereto affixed my signature in the presence of two witnesses.

ELMER E. FISHER.
